(57) **CLAIM**

We claim the ornamental design for a carrying case, as shown and described.

DESCRIPTION

FIG. 1 is a top perspective view of a carrying case comprising a new, original and ornamental design, in a closed configuration;

FIG. 2 is a bottom perspective view of the carrying case of FIG. 1, in the closed configuration;

FIG. 3 is a top view of the carrying case of FIG. 1, in the closed configuration;

FIG. 4 is a bottom view of the carrying case of FIG. 1, in the closed configuration;

FIG. 5 is a rear view of the carrying case of FIG. 1, in the closed configuration;

FIG. 6 is a front view of the carrying case of FIG. 1, in the closed configuration;

FIG. 7 is a left side view of the carrying case of FIG. 1, in the closed configuration;

FIG. 8 is a right side view of the carrying case of FIG. 1, in the closed configuration;

FIG. 9 is a top perspective view of the carrying case shown in an alternate open configuration and depicting the internal arrangement;

FIG. 10 is a top view of the carrying case of FIG. 9, in the open configuration;

FIG. 11 is a bottom view of the carrying case of FIG. 9, in the open configuration;

FIG. 12 is a front view of the carrying case of FIG. 9, in the open configuration;

FIG. 13 is a rear view of the carrying case of FIG. 9, in the open configuration;

FIG. 14 is a right side view of the carrying case of FIG. 9, in the open configuration; and

FIG. 15 is a left side view of the carrying case of FIG. 9, in the open configuration.

FIG. 16 is a top perspective view of the carrying case of FIG. 1, in an open configuration and depicting a second example embodiment of an internal arrangement; and,

FIG. 17 is a top view of the carrying case of FIG. 1, in the open configuration and depicting the second example embodiment of FIG. 17.
